(No Model.)

W. W. BALDWIN.
METALLIC BED.

No. 605,660.

Patented June 14, 1898.

UNITED STATES PATENT OFFICE.

WILLIAM W. BALDWIN, OF CLEVELAND, OHIO, ASSIGNOR TO THE CLEVELAND CO-OPERATIVE STOVE AND HOLLOW WARE FOUNDRY COMPANY, OF SAME PLACE.

METALLIC BED.

SPECIFICATION forming part of Letters Patent No. 605,660, dated June 14, 1898.

Application filed June 4, 1897. Serial No. 639,410. (No model.)

To all whom it may concern:

Be it known that I, WILLIAM W. BALDWIN, a citizen of the United States, residing at Cleveland, in the county of Cuyahoga and State of Ohio, have invented certain new and useful Improvements in Metallic Beds; and I do hereby declare the following to be a full, clear, and exact description of the invention, such as will enable others skilled in the art to which it appertains to make and use the same.

The object of my invention is to provide a cheap and ornamental rail adapted to surmount the ordinary straight side bar of a metal bed, and thereby increase the attractive appearance of the bed and hold the bedding more neatly in place.

My improved bed-rail is adapted to be furnished separately and secured in a few minutes to the side bar of a proper-sized metal bed. In order that it may be made cheaply enough to be salable, I make it of several cast sections, which engage with each other and are secured at their upper edges to a substantially straight horizontal bar.

The invention consists of a bed-rail so made. It consists also of certain features of construction for the efficient securing together of the parts of the rail or of the rail and the bed, as hereinafter described, and pointed out in the claims.

The drawings clearly disclose my invention.

Figure 1 is a perspective view of a metal bed having my improved side rail. Fig. 2 is a top view of a portion of the rail at and near one end thereof. Fig. 3 is a vertical section of the rail, being taken on the line 3-3 of Fig. 1; and Fig. 4 is a side elevation, on an enlarged scale, of one of the intermediate sections of which the rail is composed.

Referring to the parts by letters, A represents the four corner-posts of a metal bed, and B the ordinary angle-iron side bar, the same being supported from the posts. The plates *a* may be secured to posts A to hide the union between said side bars and posts.

My improved additional side rail (represented by C) stands above and just outside the bar B and is supported by that bar through the intervention of clips D, secured to the in-

ner side of the rail C and being offset, whereby they extend over the top of the bar B and project down on its inner side, while the rail C itself extends down a short distance on the outside of the bar. The side rail is secured at its ends to posts A by means of the clips E. Each clip is adjustably secured to the rail by the bolt F and the thumb-nut *f*, and thus it may be tightened to clasp the bed-post between itself and the rail C or loosened to allow the removal of said rail.

The rail is made of several cast sections *c*', which, with the exception of the end sections, are just alike. The end sections *c*' are similar, but are "rights and lefts." One of the intermediate sections *c* is shown in Fig. 4. In the bed shown there are four of these sections, though a greater or less number may be used, as circumstances render expedient. The sections are more or less nearly of the same thickness throughout, except that at one end there are the lugs *c*² *c*³, which may be somewhat thicker than the rest of the metal and are offset from it, so that the lug *c*² is adapted to lap in front and the lug *c*³ to extend behind the adjacent section when they are secured in place. The end of one section over which the lug *c*² laps is preferably beveled, as shown at *c*⁴, to make a near junction. The sections are secured by bolts and nuts G to a horizontal bar H, which is preferably an angle-iron and which extends substantially from one end of the rail to the other on its inner side. The lower line of the end sections *c*' extends upward, as at *c*⁵, so as to clear the plates *a*; while the upper line *c*⁶ also extends upward to more efficiently brace the rail, to increase its attractiveness to the eye, and to furnish a support for the clamp E.

A rail of the above-described construction may be very cheaply made, but three comparatively small patterns being necessary for the casting. I have found it practically impossible to cast the rail in one piece and make it as light as desired, as the metal cools off before it has flowed the great distance required. My rail is light, neat, and at the same time has all the strength and rigidity required.

In installing the rail the clips E are first

loosened, the rail set over the side bar with its lower edge projecting on the outside of that bar, and the clips D extending on the inner side of the bar. The clips E, which have been depending loosely, are then turned up to be on the inner side of the posts A and are bolted tightly in place by the thumb-nut f. The rail is then securely held in place until a reversal of the operations causes its removal.

It will be seen that the rail may be conveniently removed temporarily for cleaning purposes, if desired.

I claim—

- 15 1. A side rail for a bed, adapted to be removably secured to the bed, and consisting of a longitudinal bar having secured to it separate contacting sections of metal, substantially as described.
- 20 2. A bed-rail composed of separate contacting sections of metal free at their lower ends and bound together by a longitudinal bar, substantially as described.
- 25 3. A bed-rail composed of separate sections of metal secured at or near their upper ends to a longitudinal bar and having their lower ends free, said sections engaging with each other near their lower ends, substantially as described.
- 30 4. A bed-rail composed of a plurality of sections having lugs on one of their ends by which they are adapted to engage with their next neighbor, and a longitudinal bar to which they are all secured, substantially as described.
- 35 5. A bed-rail composed of a plurality of sections secured near their upper ends to a longitudinal bar, and some of said sections having near their upper ends the lug c² which extends over the next section, and near the

lower ends the lug c³ which extends behind that section, substantially as described.

6. A bed-rail composed of a plurality of sections secured to a longitudinal bar and having on its rear side clips adapted to engage with the side bar of a metal bed, and having near its ends clips adapted to engage with the bed-posts, substantially as described. 45

7. The combination with a bed having posts A and a side bar B, of a separable rail engaging with and supported by the bar B, and secured to the posts A, substantially as described. 50

8. The combination with a bed having posts A and a side bar B, of a separable rail embracing the said side bar between the lower edge of the rail, and clips D carried on the inner side of the rail and embracing the said posts between the ends of the rail and clips E carried on the inner side of the rail, substantially as described. 55

9. The combination with a bed having posts A, plates a and a side bar B, of a separable rail C supported by the bar B and having its lower edge extending upwardly at its ends 65 to clear the plates a, said rail having its upper edge extending upwardly at the ends and being secured to the posts at said upwardly-extending ends, substantially as described.

10. A section for a bed-rail, consisting of 70 a body C having integrally the lug c², the lug c³ and the beveled portion c⁴ arranged substantially as shown.

In testimony whereof I affix my signature in presence of two witnesses.

WILLIAM W. BALDWIN.
